NURSING BOTTLE

Benjamin Tauf, Chicago, Ill., assignor to Isadore
S. Rosin, Chicago, Ill.

Application April 21, 1934, Serial No. 721,801

2 Claims. (Cl. 215—11)

This invention relates to a nursing bottle and more particularly to a construction in which a flow of air takes place between the exterior and interior of the bottle or nipple to destroy or partially destroy the vacuum therein.

An object of the invention is to provide a nursing bottle and nipple equipped with extremely simple means by which air is allowed to flow into the bottle or nipple while, at the same time, the flow of milk therefrom is prevented. The invention also contemplates means for controlling and preventing the flow of air into the bottle. Other specific objects and advantages will appear as the specification proceeds.

15 The invention is shown, in preferred embodiments, by the accompanying drawing, in which—

Figure 1 is a broken sectional view of a bottle constructed in accordance with my invention and equipped with a closure cap; Fig. 2, a view similar 20 to Fig. 1, but showing the neck of the bottle equipped with a nipple; Fig. 3, a developed view of the bottle neck showing the air-flow passage therein; Fig. 4, a sectional view of a modified form of bottle equipped with a nipple; Fig. 5, a 25 developed view of the bottle neck shown in Fig. 4 with the air-flow passages therein; Fig. 6, a broken sectional view of a nipple having an air-flow passage therein and embodying my invention; and Fig. 7, a transverse sectional view, the 30 section being taken as indicated at line 7 of Fig. 6.

In the illustration given in Figs. 1, 2, and 3, 10 designates a bottle equipped with a neck 11. The neck 11 is provided near its base with an 15 enlarged threaded portion 12, and at its top portion with an annular bead 13. Starting at a point between the threaded portion 12 and the bead 13 is a tiny air-flow passage or groove 14 which, as shown more clearly in the developed 20 view of Fig. 3, extends spirally around the neck 11 and then cuts through the bead 13 at 15.

A closure cap 16, as shown more clearly in Fig. 1, is provided at its lower end with threads 17 engaging the threaded area 12 of the neck. 25 When the cap is secured into the position shown in Fig. 1, the dished top wall 18 of the cap fits snugly about the bead 13 and forms an effective seal therewith. It will be noted that the top wall 18 seals off the air-flow passage 15 through 30 the bead 13. Also, the interlocking threaded portions 17 of the cap and 12 of the neck prevent the flow of air into groove 14.

When the nipple 19 is placed in position, as shown more clearly in Fig. 2, the lower end of 35 the air-flow passage 14 extends below the bead

20 of the nipple and thus air is permitted to pass into the groove. It will be noted that the wall of the nipple cooperates with the groove 14 to provide an air-flow passage extending outside 5 the nipple and neck and communicating through the passage 15 in the bead 13 with the interior of the nipple and bottle neck. The air passage is preferably of sufficiently small dimensions and of sufficient length to prevent the flow of milk therethrough.

In the modification illustrated in Figs. 4 and 5, the bottle neck 21 is provided with a vertical groove 22 on one side of the bottle and on the opposite side of the bottle, a second vertical groove 23 through the bead 24. It will be noted 10 that the nipple 19 forms with the bead 24 a natural annular groove 25 just under the bead. With this annular passage, the diametrically opposed vertical grooves 22 and 23 communicate. In other words, the grooves 22 and 23 are connected by the annular channel 25. With the construction shown in Fig. 4, air passes through 15 the groove 22 below the bead 20 of the nipple and thence into the annular channel 25, and thence through groove 23 into the interior of the 20 nipple.

With the construction shown in Figs. 4 and 5, as well as the construction shown in Figs. 2 and 3, the flow of air into the nipple can be regulated or stopped by drawing the bead 20 of the nipple 30 upward so as to bear against the bead of the bottle neck. This movement tends to seal the vertical passages 15 or 23, as well as the annular passage below the bead of the bottle neck. A slight pressure of the bead 20 in an upward direction 35 does not stop the flow of air, but merely reduces the flow.

If desired, the neck of the bottle may be left plain; that is, without grooves or openings therein, while the nipple may be provided with air-flow passages. In the illustration given in Figs. 6 and 7, a nipple 26 is provided with a substantially vertical air passage or groove 27 communicating with a curved passage or groove 28, the latter passage communicating in turn with a vertical groove 29. The groove 27 opens at the bottom of the bead 30 so as to admit air thereto, while the vertical groove 29 extends above the bead of the bottle. With this construction, air 50 is admitted through a tortuous passage into the interior of the nipple and bottle neck. To prevent the air-grooves from collapsing under pressure, I prefer to reinforce the nipple at a point adjacent the grooves as indicated by the numeral 31. 55

While I have shown specific methods of providing air-flow passages in the neck or in the nipple, it will be understood that other forms of holes or grooves may be employed to provide for the entrance of air while preventing the out flow of milk. Grooves may be preferred because of the simplicity and cheapness of construction. For example, the neck of the bottle may be formed with the grooves illustrated without adding anything to the cost of forming the bottle, except for the original die.

The form of cap shown in Fig. 1 is particularly useful in connection with the present invention in that it forms a seal with the bottle neck below the entrance to the groove and also because it forms a seal with the bead of the bottle neck closing the passage through the bead. Such a cap prevents contamination of the milk by means of air flow.

The foregoing detailed description has been given for clearness of understanding only, and no unnecessary limitations should be understood therefrom, but the appended claims should be construed as broadly as permissible, in view of the prior art.

I claim:

1. In combination, a bottle having a hollow neck equipped at its top with a bead extending laterally beyond the contour of said neck, said bead having a groove therein terminating at the base of the bead, said neck being provided with a groove on the opposite side from said bead groove and terminating below said bead, and a nipple engaging said neck and adapted to be pressed against said bead to close the groove 10 therein. 5

2. In combination, a bottle having a neck enlarged at its top to form a laterally extending bead, said neck being of reduced size below said bead, and a nipple engaging said neck and providing normally with said bead an annular channel about said neck, said bead and said neck being provided with means co-operating with said nipple to provide non-communicating air-flow passages establishing communication between said annular channel and the interior of said nipple, said nipple being adapted to be pressed against said bead to close the air passage leading into said nipple. 15 20
